UNITED STATES PATENT OFFICE.

HARVEY E. PHILLIPS, OF DETROIT, MICHIGAN, ASSIGNOR TO THE DAYTON ENGINEERING LABORATORIES CO., A CORPORATION OF OHIO.

BINDING-POST.

Specification of Letters Patent. Patented Dec. 11, 1917.

1,249,481.

Application filed January 10, 1913. Serial No. 741,279.

To all whom it may concern:

Be it known that I, HARVEY E. PHILLIPS, a citizen of the United States, residing at Detroit, county of Wayne, and State of Michigan, have invented certain new and useful Improvements in Binding-Posts, of which the following is a full, clear, and exact description.

This invention relates to improvements in binding or terminal posts for securing the terminals of connectors, or clips of any type, firmly in position, but which permits the ready detachment of the connector or clip from the binding post.

One of the objects of this invention is to so combine the elements thereof that the structure will be simple and compact, and especially adaptable to be used in places, wherein economy of space is desired or essential.

Another object of the present invention is to provide a binding post, which will facilitate the application and removal of the connectors or clips therefrom.

A further object of the present invention is to so combine the terminal post and the clip or connector, to be secured thereto, that the said clip or connector will be positively locked or latched in applied position, thus preventing the accidental removal of said clip, and also preventing the inadvertent displacement thereof.

A still further object of the present invention is to provide means for permitting the movable element or elements of the binding post to be withdrawn from their normal position and maintained in an inoperative position, thus facilitating the application and removal of the clips, to and from the said post.

With the above and incidental objects in view, there is shown in the accompanying drawing, a preferred form of one embodiment of my present invention, a detail description of which will now be given.

In the drawings:

Figure 1 is a vertical sectional view taken on the line 1—1 of Fig. 2, of a terminal post embodying the present invention.

Fig. 2 is a view in side elevation of the 50 terminal post shown in Fig. 1.

Fig. 3 is a view in elevation of a modified form of the terminal post shown in Figs. 1 and 2.

Fig. 4 is a view similar to Fig 3, but showing the movable element of the terminal post in inoperative or non-clamping position.

Fig. 5 is a perspective view of one form of the terminal clip embodied in the present invention.

In Figs. 1 and 2, it will be seen that the binding post comprises a central rod or stud 20, having a flange or projection 21, formed intermediate the ends thereof and providing 65 a base for the spring pressed cap or sleeve 23, of the upper clamping element or binding post.

This cap or sleeve is counterbored, as at 24, and has the spring 25, seated in the 70 counterbored portion. A shoulder formed by counterboring said sleeve, acts as one abutment for the spring 25, and the plate 26, which is secured to the extremity of the stud 20, constitutes the opposite abutment. 75

From this construction, it will be seen that the spring 25 normally maintains the cap or sleeve 23 in contact with the shoulder 21, or at least, in contact with what may be termed the locking shoulder 27, which may 80 be formed integral with the flange 21.

The binding post described above is adapted to be employed in conjunction with a novel type of terminal clip; the novel features thereof being set forth hereinafter. 85 This terminal clip comprises a shank portion 29, provided with the head portion 30, wherein an annular opening 31, having an entrance opening 32, is formed.

In order to secure the terminal clip 28 90 against accidental removal from its applied position, the diameter of the opening 31 is made slightly greater than the diameter of the locking shoulder 27, but less than the diameter of the flange 21, while the diameter 95 of the entrance opening 32 is greater than the diameter of that portion of the stud 20, which is surrounded by the sleeve 23, but is

less than the diameter of the locking shoulder 27.

In the present invention, a further locking effect has been secured by having a projection or pin 33, secured to the flange 21, which is adapted to fit within the slot 34, formed in the adjacent clamping face of the sleeve or cap 23.

The terminal clip 28, is also recessed as at 35, so that the pin 33 will fit within the recessed portion 35, when the terminal is applied to the binding post.

Under certain conditions, it has been found advisable to provide some means, whereby the cap or sleeve 23 may be held out of operating or clamping position, in order to facilitate the removal or the application of terminal clips to the post.

The provision of the pin 33, not only acts as a means for securing and maintaining the terminal clip in its applied position, but it also provides the aforementioned means for holding the cap 23 out of operative position, inasmuch as when said cap is raised above the pin 33, and turned so that the slot 34 thereof, is removed from alignment with the pin, the cap may be released and will be held in raised position by engagement with the pin 33.

In Figs. 1 and 2, there is shown an additional clamping element. This clamping element is insulated from the structure herefore described, so that an electrical connection may be made, which may be absolutely insulated from and independent of the electrical connection secured by the outer clamping element.

The central stud 20 is, in the present instance, surrounded by an insulated sleeve 41, which has at one end, the washer or head 42, one face of which lies adjacent to the washer 21. The opposite face of this washer 42 carries a metal facing 44, which forms a bearing element for the reduced end 45 of the movable sleeve 46.

A metal tube 47, surrounds a portion of the said sleeve 41, and is reduced as at 48, thus forming the shoulder 49, which furnishes one abutment for the spring 50.

This spring is mounted in the reduced portion of the metal sleeve 47, and tends to normally maintain the movable sleeve 46, in contact with the metal facing 44 of the washer 42. The movable sleeve or clamping element 46 has an internal flange, as at 51, which forms an abutment, against which the spring normally presses, whereby this sleeve, as above stated, is maintained in contact with the metal facing 44 of the washer 42.

In a binding post of this type, a locking shoulder 52 is formed on the movable sleeve or clamping element, by reducing the clamping end thereof, as at 45, so that the termin-

nal clip which is used in conjunction with this portion of the binding post, must have its main opening of greater diameter than the reduced portion of the sleeve, while the entrance opening must be of less diameter than the diameter of the reduced portion 45, but of greater diameter than the cross sectional diameter of the metal tube, upon which the movable sleeve is mounted and which in reality forms the electrical connection.

It will, of course, be understood that this particular construction of the binding post may be provided with a locking pin to cooperate with a recess formed in the terminal clip, if it is so desired, it simply being necessary that the locking pin 53 be mounted on the movable sleeve or clamping element 46, so as to fit within a slot or groove 54, formed in the metal facing 44 of the insulated washer 42.

In Figs. 3 and 4, there is shown a modified form of the binding post illustrated in Figs. 1 and 2.

This modified structure shown in these figures, comprises a terminal post of conductive material, whereby the terminal connected thereto, may have a common electrical connection with any circuit to which the body of the binding post may be connected.

The structure of the post shown in Fig. 3, is substantially the same as that described in connection with the description of the similar elements included in Figs. 1 and 2, and therefore, no further detailed description is deemed necessary.

While I have shown preferred forms of embodiment of the present invention, it should be understood that various changes and modifications of the elements and combinations of elements, comprising the present invention, may be made without departing from the spirit and scope of the present invention.

What I claim is as follows:

1. In a binding post, the combination with a plurality of slideable clamping elements; of a stationary element; resilient means for maintaining said slideable elements in clamping position relative thereto; and means whereby said slideable elements may be maintained in non-clamping position against the normal tendency of said resilient means.

2. The combination with a binding post, comprising a supporting stud having a stationary clamping element secured thereto; of a co-operating movable clamping element mounted on said stud; and a locking shoulder intermediate said stationary and movable clamping elements and of greater diameter than the stud; of a terminal clip comprising a plate provided with a central

opening of greater diameter than the locking shoulder, and an entrance opening to said central opening of less diameter than the diameter of the locking shoulder but of greater diameter than the diameter of the stud; said plate being provided with a locking recess; and a locking pin carried by said stud for engagement therein, whereby, said

terminal clip will be prevented from axial displacement.

In testimony whereof I affix my signature in the presence of two subscribing witnesses.

HARVEY E. PHILLIPS.
